DEHYDRATING APPARATUS

William B. Goding, Zellwood, Fla., assignor to
 Florida Humus Company, Zellwood, Fla., a
 corporation of Florida

Application April 23, 1935, Serial No. 17,883

4 Claims. (Cl. 100—47)

This invention relates generally to apparatus for removing liquid from mixtures of liquids and solids; and, more particularly, to apparatus for dehydrating peat humus.

5 Peat humus is ordinarily obtained from a watery muck; and before it can be used for fertilizing purposes, must have practically all of the water separated therefrom. It is the main object of this invention to effect this water separation 10 economically and expeditiously.

Other objects of the invention will become apparent as the detailed description thereof proceeds.

In the drawings:

15 Figure 1 is a top plan view of the dehydrating apparatus embodying the present invention;

Figure 2 is a central longitudinal section through the apparatus shown in Figure 1, parts of the apparatus being shown in elevation;

20 Figure 3 is a central vertical section, to an enlarged scale, illustrating the structural details of one of the dehydrating cylinders forming part of the apparatus;

Figure 4 is a top plan view of squeezer mechanism forming part of the apparatus;

25 Figure 5 is a central longitudinal section taken through the mechanism shown in Figure 4;

Figure 6 is a horizontal section to an enlarged scale of one of the dehydrating cylinders forming 30 part of this apparatus;

Figure 7 is a transverse section of one of the squeezer cylinders with parts of scraper mechanism connected thereto;

Figure 8 is a perspective of one of a number of 35 scrapers embodied in this apparatus; and

Figure 9 is a sectional detail of one of the floating bearings which adapt one of the squeezer cylinders for movement bodily toward and from the other squeezer cylinder.

40 As shown in the drawings, the apparatus comprises a substantially rectangular tank 1, having the bottom 2 thereof suitably supported on standards 3. Side walls 4 and 5, and an end wall 6, are suitably secured to the bottom 2, the end wall

45 6 being secured to the side walls 4 and 5 at the inlet end of the tank 1. An end wall 7, at the outlet end of the tank, connects the upper part of the side walls 4 and 5 to each other, and is spaced upwardly from the bottom 2, to form the 50 outlet opening 8.

Within the tank 1 a series of cylindrical perforated drums 9, 10, 11 and 12 are mounted to rotate about substantially vertical axes. These drums are similar in every respect; therefore, it 55 will only be necessary to describe one in detail,

in order to disclose their structures. For this purpose, reference is made to Figures 3 and 6 of the drawings, which show in detail the various parts of the drum 9. The drum 9 has its inner periphery suitably secured to the spiders 13, 14, 5 and 15, spaced apart along the shaft 16 and suitably secured thereto. The drum 9 is closed at its upper end by a perforated plate 17, and the cylindrical body of the drum is likewise perforated to permit water to flow therethrough from the humus being subjected to a dehydrating operation.

The lower end of the drum 9 is open, and is located over an outlet opening 18 formed in the bottom 2 of the tank. A discharge funnel 19, secured to the bottom of the tank, extends downwardly to discharge liquid into a trough 20, arranged directly below the funnel 19 and suitably supported by the standard 3. The shaft 16 has its lower end rotatably mounted in a bearing bracket 21, secured to the vertical flange 22 of an angle iron strap 23, which extends through the funnel 19 and has its horizontal flange secured to the bottom 2 by means of the bolts 24 and 25. (See Figure 3.)

The upper end of the shaft 16 is mounted to 25 rotate in a bearing bracket 26, bolted or otherwise secured to a bulkhead 27, which extends across the tank between the side walls 4 and 5 thereof and directly above the top of the drum 9. A thrust bearing 28 is interposed between the top 30 of the bearing bracket 26 and a sleeve 29, adapted to be fixed to the shaft by means of a set nut 30. The sleeve 29 can be positioned so as to hold the open lower end of the drum 9 slightly above the bottom 2 of the tank 1, to permit the free rotation of the said drum 9 within the tank 1. A seal 31 is fixed around the lower end of drum 9 to the bottom 2, in order to prevent leakage of humus under the lower open end of the cylinder 9 into the outlet funnel 19.

The shaft 16 extends through a bearing 32 fixed to a cross bar 33 secured at its opposite ends to the upper edges of the side walls 4 and 5. A bevel gear 34, fixed to the upper end of the shaft 16, meshes with a bevel pinion 35 which is fixed to a drive shaft 36 extending lengthwise of the tank 1 and rotatably mounted in bearings 37, 38, 39, and 40 secured to the respective cross bars 33 of the cylinders 9, 10, 11, and 12.

The shaft 36 has its inlet end rotatably mounted in a bearing bracket 41 fixed to the end wall 6; and a pulley 42 is fixed to the end of the shaft 36 to be rotated by a belt 43 to effect rotation of the shaft 36, with the consequent simultaneous rotation of the drums 9, 10, 11, and 12. It will be ap-

parent from the arrangement of bevel gearing in Figures 1 and 2 of the drawings, that each drum rotates in a direction opposite to the direction of rotation of the drum or drums adjacent thereto.

5 For example, drums 9 and 11 may be considered as rotating in a clockwise direction, looking down on the apparatus; while drums 10 and 12 rotate in an anti-clockwise direction.

The humus is caused to move through a tortuous path from the inlet to the outlet end by an arrangement of baffle plates or scrapers connected to the side walls of the tank and having their free edges in frictional contact with the cylindrical surfaces of the drums. As shown in 15 Figure 1 of the drawings, a baffle plate 44 is arranged at the inlet side of the tank 1, in order to force the humus to pass around the drum 9 and between the wall 4 and the surface of said drum 9.

A baffle plate 45, preferably formed of sheet 20 steel or other springy material, has one of its edges suitably fixed to the wall 4. The other edge of this plate 45 is provided with a scraper shoe 46, preferably of wood or fiber, and adapted to be held in yielding contact by the resilience of the 25 material in the plate 45, against the cylindrical surface of the drum 10. Similarly, a plate 47 provided with a scraper shoe 48 is suitably fixed to the wall 5, so as to maintain the shoe 48 in yielding scraping contact with the drum 9. Plates 30 49, 50, 51, and 52 provided with scraper shoes quite similar to the scraper shoes 46 and 48 on the plates 45 and 47, are secured to the walls 4 and 5 in the same manner, in order to provide the tortuous path for the humus, during its passage 35 from the inlet to the outlet end of the tank 1.

It will be apparent from the drawings that the bulkheads 27 retard the flow of the humus through the tank, and force the same to pass through the tank in contact with the perforated surfaces of the 40 drum. Additional scrapers may be used to remove the humus from the cylindrical surfaces of the drum. One of these scrapers 52', shown in perspective in Figure 8 of the drawings, is pivoted at the upper end of its rear edge 53 to a bracket 45 54 which is suitably secured to the bulkhead 27. The lower end of the scraper 52' is pivoted suitably to the bottom 2 of the tank 1. A spring 55 having one end secured to the bracket 54, is bent to extend around the edge 53 of the scraper 52' 50 and to contact with one side of the scraper 52' to force the free edge thereof into yielding contact with the cylindrical surface of the drum 9. A scraper 56, similar in every respect to the scraper 52', is pivoted at its lower end to the bottom 55 of the tank 1, and at its upper end is pivoted to a bracket 57, fixed to the cross bar 53. A coil spring (not shown) similar to the spring 55, is used to hold the scraper 56 with its free edge in yielding scraper contact with the cylindrical 60 surface of the drum 9.

It will be apparent from inspection of Figure 1 of the drawings, that the humus is forced by the rotation of the drums through the discharge outlet 8 and into a discharge hopper 58 leading to a 65 pair of perforated squeezer drums 59 and 60. The drum 60 has its cylindrical body secured to I-beams 61 angularly spaced apart and secured to the spiders 62, which in turn are suitably fixed to a shaft 63. The lower end of the shaft 63 is mounted to rotate in a bearing bracket 64, secured between cross bars 65 and 66, having their ends fixed to the spaced apart parallel channel iron members 67 and 68, forming part of the framework for the squeezer drums. The upper 70

end of the shaft 63 is mounted to rotate in a bearing bracket 69, fixed between cross bars 70 and 71, likewise secured to the channel irons 67 and 68.

A ballbearing sleeve 72 rests upon the plates 70 5 and 71 directly above the bearing bracket 69 and forms the lower race member of a thrust ball-bearing, the other member 73 of which serves as a support for a sprocket gear 74. A clamping sleeve 75 is slidably mounted on the shaft 63 and 10 may be secured thereto by means of a set screw 76 to clamp the sprocket gear 74 firmly to the shaft 63. The squeezer drum 59 is identical, so far as structure is concerned, to the squeezer drum 60. However, the bearings 77 and 78 for 15 its shaft 79, are mounted to slide between the pairs of crossbars 65-66 and 70-71, respectively, in order to provide for a yielding pressure of the drum 59 against the drum 60. As shown in Figure 9 of the drawings, the bearing 78 is provided with grooves 79 and 80 adapted to receive the tongues 81 and 82, which project from plates 83 and 84, respectively, suitably secured between the crossbars 70 and 71.

The bearing 78 is pivoted to a link 85 (see Figure 25 5), the other end of which is pivoted at the bend of a bellcrank lever 86, which at the end of its small arm, is pivoted to a plate 87', projecting beyond the ends of the crossbars 70 and 71 and suitably secured thereto. The horizontally extending long arm 87 of the bellcrank lever, is provided with a series of notches 88, adapted to receive a loop 89 carrying a weight 90. The lower bearing 77 is slidably mounted between the cross-bars 65 and 66 and is connected by a 35 link 91 to the bend of a bellcrank lever 92, which has the end of its short arm pivoted to a bracket 93, suitably fixed to the channel iron 66. A link 94 is connected at its opposite ends to the long arms of the bellcrank levers 86 and 92, in order that 40 both of the levers may be operated simultaneously to hold the drum 59 in yielding contact with the drum 60.

The lower ends of the squeezer drums 59 and 60 45 are open and discharge liquid therefrom into the trough 20, which is inclined downwardly in opposite directions toward the center of the framework to discharge its contents through a discharge pipe 96. (See Figure 2.)

A rubber sealing strip 97 is secured to the channel iron 68 and extends from top to bottom of the drum 59. Similarly, a rubber sealing strip 98 is secured to the channel iron 67 and extends throughout the length of the squeezer drum 60. Scrapers 99 and 100 extend throughout the 55 lengths of the drums 59 and 60, and are fixed to levers 101 and 102 which are fulcrumed between their ends on supporting members extending from the framework. A coil spring 103 connects the outer arms of the levers 60 101 and 102 to each other to hold the scrapers 99 and 100 in yielding contact with the cylindrical 65 surfaces of the squeezer drums.

The upper end of the shaft 79 is provided with a 70 sprocket gear 104; and a sprocket chain 105 engages gears 74 and 104 to effect rotation of the drums 59 and 60 in opposite directions, as shown clearly in Figure 1 of the drawings. A spout 106 extends across the lower open ends of the squeezer 75 drums to receive the dehydrated humus removed by the scrapers 99 and 100. It will be noted that the squeezer drums are inclined rearwardly, so that water squeezed from the humus flows through the perforations of the drums into the 75

interior thereof to be discharged through their open lower ends into the trough 20. The humus scraped off from the drums drops into the discharge chute 106.

5 It is to be understood that the invention is not to be considered as limited to the specific construction and arrangement described herein, since it is evident that many changes may be made without departing from the scope of the invention as defined by the claims appended hereto.

10 What I claim is:

15 1. Dehydrating apparatus comprising a substantially horizontal tank having an opening through the bottom thereof, a drum having a wall at one end and the other end open, and being perforated throughout its cylindrical body and end wall, means for mounting said drum to rotate with its open end surrounding the opening in said bottom, and means for rotating said drum 20 to move horizontally the material being dehydrated from one end to the other end of said tank, said other end having a discharge outlet, and means at said outlet for receiving and squeezing material from said discharge outlet.

25 2. Dehydrating apparatus comprising a tank having a series of openings through the bottom thereof, cylindrical drums, each having a wall at one end and the other end open and perforated throughout its cylindrical body and end wall, means for mounting said drums to rotate with their open ends surrounding the openings in said bottom, and means for rotating said drums to move the material from one end to the other end of said tank, said other end having a discharge outlet, 30 and means at said outlet to receive and squeeze the material discharged from said tank through said outlet.

outlet, and cylindrical drums mounted to rotate about parallel axes inclined to the vertical at the discharge outlets to receive and squeeze between their adjacent surfaces the material discharged from said outlet.

5

3. Dehydrating apparatus comprising a tank having a series of openings through the bottom thereof, cylindrical drums, each having a wall at one end and the other end open and perforated throughout its cylindrical body and end wall, 10 means for mounting said drums with their open ends surrounding the openings in said bottom, means for rotating said drums so that each drum rotates in a direction opposite to the direction of rotation of the adjacent drum, and 15 means for causing the material to move in one direction in a tortuous path along the cylindrical surfaces of said drums toward a discharge outlet at one end of said tank.

4. Dehydrating apparatus comprising a tank having a series of openings through the bottom thereof, cylindrical drums, each having a wall at one end and the other end open and perforated throughout its cylindrical body and end wall, 20 means for mounting said drums to rotate with their open ends surrounding the openings in said bottom, means for rotating said drums to move the material from one end to the other end of said tank, said other end having a discharge outlet, 25 and means at said outlet to receive and squeeze the material discharged from said tank through said outlet.

WILLIAM B. GODING.
